UNITED STATES PATENT OFFICE.

CLARENCE EDWARD ANABLE, OF SACRAMENTO, CALIFORNIA.

SERVING APPARATUS.

1,299,413.

Specification of Letters Patent.

Patented Apr. 8, 1919.

Application filed August 3, 1918. Serial No. 248,095.

To all whom it may concern:

Be it known that I, CLARENCE E. ANABLE, a citizen of the United States, residing at Sacramento, in the county of Sacramento and State of California, have invented certain new and useful Improvements in Serving Apparatus, of which the following is a specification.

My invention relates to certain new and useful improvements in serving apparatus. A leading object of the invention is to provide means for dispensing toilet-paper from a holder, the holder being of that type which is supplied with means for preventing the roll of paper from being removed bodily from the mandrel after the roll has once been put in place in the holder, said holder having, also, means of preventing the spinning or paying off too rapidly of the paper from the roll, and likewise preventing the abstraction of the roll.

With the above and other objects in view, my invention consists of the parts and the constructions, arrangements and combinations of parts which I shall hereinafter describe and claim.

In the accompanying drawing forming part of this specification, and in which similar reference characters indicate like parts in the several views:—

Figure 1 is a perspective view of a roll-holder embodying my invention.

Fig. 2 is a longitudinal sectional view of the same.

Fig. 3 is an enlarged view of the mandrel removed showing the locking pins in place.

In carrying out my invention, I employ a suitable support. This will depend somewhat on the position the device is to occupy when in use and hence the design of said support will be subject to more or less modification. In any event, the support will preferably include a pair of standards A outstanding from a suitable base, which may be a wall or other surface to which the holder is fixed. The outer ends of the standards are formed with openings a which provide bearings for appropriate locking pins, which I shall hereinafter describe. Between

the standards, A, the core or mandrel B is mounted. This may be made of wood or other appropriate material, said core or mandrel having a diameter adapted more or less to that of the usual card-board tube or cylinder, C, with which the roll of paper, D, is usually supplied, whereby the roll

may be readily slipped over the core or mandrel when assembling the device for use.

The ends of the core or mandrel are formed with holes b which are off-center or eccentric to the axis of the core or mandrel and are adapted to register with the bearings a in the supporting standards A, so that said holes will readily admit the locking pins, D. These pins form the journals of the core or mandrel and they are each formed with a circumferential groove c. The core or mandrel is also formed with transverse kerfs or slots d which are sufficiently deep to intersect the bore of the holes b, said core or mandrel having secured to its outer surface a bowed spring, or springs, E, whose outer ends are bent at about right angles to the length of the spring and are adapted to be registered with and to enter the aforesaid kerfs or slots d and be engaged in or with the annular grooves c formed in the locking pins, whereby said pins are locked against withdrawal. As the springs are bowed, it will be manifest that the act of forcing the core or mandrel into the central tube of the roll of paper, will result in flattening or depressing the springs and thus forcing the bent ends thereof into the kerfs or slots c and into locking engagement with the grooves of the locking pins. This operation secures the pins against removal and prevents the roll of paper from being removed until the entire contents thereof have been unwound, and the remaining card-board tube is destroyed, which latter act is necessary to release the bowed springs for they must be allowed to expand to withdraw their ends out of locking engagement with the pins.

The end of the core or mandrel is also provided with an arm F, counterweighted if desired, and on the inner face of one of the standards A is a fixed lug e. As the paper is pulled forward to detach a sheet— it being understood that the web of paper is usually weakened or scored at points to form separate sheets—the core or mandrel is partially rotated and the arm F is moved with the core, backward and upward, and until it strikes the lug e, when further rotation of the core is prevented. The continued pull on the web now detaches a sheet of paper and as the sheet is removed the core, largely because of its eccentric mounting, immediately returns to its normal position. In other words, the core is oscillatory

and as each sheet is grasped and pulled, the core and roll are rocked to bring another weakened or scored line free from the roll and detach the sheet, and then freeing the roll and permitting it to return to its normal position.

To apply the roll of paper, the core or mandrel is inserted into the center of the roll, depressing the springs, and the pins, D, 10 are pushed through the standards and into the ends of the core until their grooves interlock with the bent ends of the springs, when the roll will be supported ready for use.

Having thus described my invention, what 15 I claim and desire to secure by Letters Patent is:—

1. A roll holder having in combination a support, a mandrel or core mounted for oscillating movement therein, said support 20 and mandrel having holes adapted to register, means including a locking pin removably mounted in said holes and forming the axis about which the mandrel oscillates, said pin being readily separable endwise from 25 said support and being pushed through the support from the outside after the roll of paper is positioned on the mandrel, and a spring plate on the mandrel normally projecting beyond the circumference thereof 30 and depressible when the mandrel is inserted into the open center of a roll of paper, said mandrel being recessed between its ends and

said spring plate having a free end and said pin having a shoulder adapted to be engaged by the end of the spring to thereby automatically lock the pin in place during the insertion of the latter, said spring automatically releasing the pin only when the roll of paper has been depleted and the open center of the same has been destroyed. 35

2. In a roll holder, the combination of a support, a mandrel or core having end pins bearing in said support and mounted off-center in the mandrel and provided with annular grooves, one of said pins being at 40 each end of the mandrel and the pins being readily separable endwise from said support and being pushed through the support and ends of the mandrel from the outside after the roll of paper is positioned on the mandrel, and a spring plate fixed to the mandrel and normally projecting toward each end thereof and beyond the circumference of the mandrel, said mandrel having narrow transverse slots, one near each end, intersecting 45 the bore of the pins, and said spring having bent end portions compressible into said slots and adapted to be locked into engagement with the grooves of the pins when the mandrel is inserted into the open center of a roll 50 of paper or other fabric. 55

In testimony whereof I affix my signature.

CLARENCE EDWARD ANABLE.
